FIG. 1 is a front, top, and left side perspective view of a pack holder with compartment for storing used tobacco consumables;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines in the drawings depict portions of the pack holder with compartment for storing used tobacco consumables that form no part of the claimed design.

1 Claim, 7 Drawing Sheets
